UNITED STATES PATENT OFFICE.

ANDREW J. CHURCH, OF SHERBORN, MASSACHUSETTS.

CARRIAGE-JACK.

SPECIFICATION forming part of Letters Patent No. 287,625, dated October 30, 1883.

Application filed September 20, 1883. (No model.)

To all whom it may concern:

Be it known that I, ANDREW J. CHURCH, of Sherborn, in the county of Middlesex, State of Massachusetts, have invented a certain new and useful Improvement in Carriage-Jacks, of which the following is a description sufficiently full, clear, and exact to enable any person skilled in the art or science to which said invention appertains to make and use the same, reference being had to the accompanying drawings, forming a part of this specification, in which—

Figure 1 is an isometrical perspective view of my improved carriage-jack, and Fig. 2 a vertical longitudinal section of the same.

Like letters and figures of reference indicate corresponding parts in the different figures of the drawings.

My invention relates more especially to that class of carriage-jacks which are provided with levers, and are designed for use in lifting the axle of the carriage to raise a wheel from the ground, in order that it may be removed from the spindle for greasing or repair; and it consists in a novel construction and arrangement of the parts, as hereinafter more fully set forth and claimed, by which a simpler, cheaper, and more effective device of this character is produced than is now in general use.

The nature and operation of the improvement will be readily understood by all conversant with such matters from the following explanation, its extreme simplicity rendering an elaborate description unnecessary.

In the drawings, A represents the base; B the standards or uprights; C, the lever; D, the retaining-bar, and E the lifting bar or slide.

The standards have their lower ends framed into the base, and are arranged in such a manner as to leave a space between them sufficiently wide to receive the lever C and bars E D.

The bar E is provided with an elongated slot, x, and a series of notches, m, and is fitted to work vertically between the standards in the head of the jack on the pins f f, which pass laterally through said slot and are supported in the standards.

The lever C is pivoted at g in the body of the jack, and jointed to its short arm at h there is a vertically-arranged pitman or rod,

G, which passes through a slot, i, in the bar E, and has its upper end jointed to said last-named bar at t.

The retaining-bar D is provided on its under side at its inner end with a series of serrations or teeth, l, adapted to engage a pin or stop, n, disposed in the standards B, its outer end being pivoted at r in the outer end of the lever C.

A cross-beam, H, is secured between the standards to hold them properly apart, the beam being connected with the base A by an inclined brace, L, for steadyng the standards and preventing them from working loose in the base.

In the use of my improvement the top of the bar E, or one of the notches m, is placed under the axle of the carriage, and the outer end of the lever C depressed until the wheel is raised the desired distance from the ground. The teeth l are so formed as to incline toward the outer end of the lever, and when the lever is forced down to raise the superincumbent weight on the bar E the teeth slide over the pin n, and when the lever is released the teeth engage the pin and lock the lever, thereby preventing the bar E from descending, and holding the wheel in an elevated position in a manner which will be readily obvious without a more explicit description. After the wheel has been greased, or whenever it is desired to lower the axle, the lever C and bar D are grasped in the hand and forced downwardly a slight distance, thereby relieving the strain on the bar D, after which the hand is closed, thereby disconnecting the serrated end of the bar D from the pin n, and the lever raised, permitting the bar E to descend and the wheel to fall to the ground.

It will be obvious that the lever C and bar D serve as a handle, by which the jack may be readily lifted and placed in position for use, and also that but one hand is required to raise the wheel and lock the jack, or to unlock the jack and lower the wheel—a very important feature in devices of this character, as one hand is usually occupied in holding the wrench or oil-can.

It will also be obvious that instead of the standards and base of the jack being framed together as described, these parts may be made

of metal and cast integral, if desired, it being understood that proper materials are to be used in the construction of all its parts, and that they are to be made in a substantial and workman-like manner.

Having thus explained my invention, what I claim is—

1. The improved carriage-jack herein described, the same consisting of the base A, standards B B, sliding bar E, pitman G, lever C, serrated retaining-bar D, stop-pin *n*, pivots *t h r*, and guide-pins *f f*, constructed, combined, and arranged to operate substantially as set forth.

15 2. In a carriage-jack substantially such as described, the serrated bar D, pivoted at its

outer end to the outer end of the lever C, said bar being arranged beneath said lever, in combination with the pin *n*, substantially as specified.

3. In a carriage-jack substantially such as described, in combination with the lever, a retaining bar or device for locking said lever when it is depressed, said bar or device and lever being adapted to be grasped at the same time, and operated by one hand to unlock the lever and permit it to rise and the wheel to fall, substantially as set forth.

20 ANDREW J. CHURCH.
